GENERATOR FOR USE WITH INTERNAL
COMBUSTION ENGINES

Charles E. Morley, Detroit, Mich.

Application June 21, 1934, Serial No. 731,682

5 Claims. (Cl. 122—24)

This invention relates to steam generators, the object being to provide a boiler associated with the automobile engine to receive the heat of the combustion gases to quickly transform a small body of water to steam, the quantity of water in the boiler being insufficient to produce pressures destructive of the apparatus.

It is further an object and feature of the invention to provide a steam generator including a boiler element carried in the casing which may be inserted in the spark plug aperture of the engine and opening to the combustion chamber whereby the combustion gases may circulate about the boiler element to heat the water.

15 It is further an object and feature of the invention to provide a steam generating apparatus consisting of a boiler element attachable to the engine cylinder as hereinafter described.

20 These and other objects and novel features of the invention are hereinafter more fully described and claimed, and the preferred form of construction of a steam generator embodying my invention is shown in the accompanying drawings in which—

25 Fig. 1 is an elevation partly in section showing one form of my improved steam generating device.

Fig. 2 is an enlarged section showing the boiler construction taken on line 2—2 of Fig. 1.

30 Fig. 3 is a section taken through the sleeve supported in the partition between the body and engine compartment.

Fig. 4 is a sectional view of another form of the device.

35 Fig. 5 is a plan view thereof.

Fig. 6 is an enlarged section taken on line 6—6 of Fig. 4.

In Fig. 1, the partition wall between the passenger and engine compartments of an automobile is indicated at 1, a portion of the engine being indicated at 2 and the combustion chamber at 3. In the engine head is a threaded aperture 4 in which the spark plug 5 is usually threaded. In this case, however, the boiler element 6 has a tubular extension 7 of the casing 8 threaded in the spark plug opening. The boiler element comprises an external casing 8 of a hollow cone like form having a cap 9 secured to the upper open end thereof in any approved manner as by threading the same thereinto. The cap 9 has a central depression 10 formed with a threaded aperture to receive the threaded end of the spark plug 5. The boiler proper consists of a cone like element 11 hollow in form and having a central aperture 12 with which the spark plug is closely

associated and in alignment with the extension 7 of the casing thus providing a passageway for gases.

On the compression stroke of the engine piston, the gases are forced into the passageway 7 and aperture 12 opening to the spark plug terminals and are ignited by the spark plug in the usual manner. Thus the heat of the burning gases is applied directly to this boiler element 11 which is spaced from the cap and walls of the casing 8 permitting the burning gases to pass about the inner and outer walls of the boiler as well as centrally thereof at the point 12.

The boiler structure, indicated generally at 6, is comparatively small, the boiler at its upper end

15 preferably for the usual automobile being about four inches in diameter and the distance from the top of the boiler to the bottom also about four inches in length. As this boiler will hold less

than one-half pint of water, the water is quickly 20 changed to steam and the radiator practically immediately will transfer heat to the passenger compartment.

There is a hollow tubular stud 13 secured to the upper end of the boiler element at one side and extends through an aperture in the

25 cap 9 provided therefor and a gasket 14 is provided about the tube 13 between the upper edge of the boiler and the cap and a similar gasket 15 is provided between the cap and the nut 16 thereon.

Thus the aperture for the tube 13 is sealed 30 to prevent an escape of steam. The steam line 17 is connected to the hollow stud 13 as by

means of a coupling 18 of any approved form. On the diametrically opposite side of the boiler

35 element 11 is a tubular stud 19 which extends outwardly through the cap in the same manner as the stud 13 and connected by a similar coupling with the return line 20. The tubular stud 19 has an extension 21 leading to nearly the

40 bottom of the boiler while the tubular stud 13 opens directly to the top of the boiler.

The partition wall 1 has an aperture for a 45 threaded sleeve 21, which sleeve, as will be understood from Fig. 3, has a slot 22 therein to receive the lines 17 and 20 which are preferably spaced apart as shown.

The end of the sleeve extends from the passenger compartment into the engine compartment and is there provided with a nut 23 and lock washer 35 and the opposite end of the 50 sleeve is provided with a large head 24 which is preferably provided with points 24a on the face thereof toward the partition 1 that are caused to cut into the partition member by the tightening of the nut 23 and thus hold the sleeve from 55

accidental rotation. The head 24 also has a bracket 25 on each of its opposite sides which brackets extend upwardly and inwardly of the passenger compartment to beneath a clamping band 26 on the motor casing, the two brackets being on diametrically opposite sides of the motor casing and suspending the motor. These brackets are outturned at the ends 28 and may be attached in any desired manner as by a bolt 29 to the radiator casing 30. It is not important what the radiator structure may be but preferably the outer shell 30 is open at 31 in the rear face and within this outer shell is a cylindrical shell 34 of hexagonal cross section having tubes 34a extending therethrough from the front to the rear through which air may be drawn. To the upper end of the shell 34 is connected the conduit 17 for the heated fluid and to the lower side is connected the return line 20. The motor casing is supported centrally of the inner radiator element 34 and a fan 32 on the motor shaft is forward of this radiator element 34 by means of which air is drawn through the tubes and across the radiator. A shutter member having the blades 33 is mounted on the shell 30, which blades may be hinged if desired to vary the direction of flow of the heated air.

The boiler element, indicated generally at 40, extends to one side only of the spark plug as will be understood from the plan view Fig. 5. It is sometimes necessary to use this construction due to the peculiarity of construction of the engine or parts associated therewith on or adjacent the upper ends of the engine cylinder which would prevent the use of a cone form of boiler structure shown in Fig. 1. In this construction of Fig. 4 there is an outer casing 41 having a comparatively thick upper wall to which is welded or otherwise secured a lower thin wall 42 and forming therewith a hollow shell. The shell has a neck 43, a portion of which may enter the socket in the engine head 44 surrounding the spark plug opening 45. This neck 43 at the bottom of the portion extending into the spark plug socket has a flanged opening indicated at 46 and in this opening is an externally flanged hollow ferrule 47 threaded into the spark plug opening 45. The ferrule 47 may be notched on opposite sides as at 48 to permit an operator to thread the same to place and to thus secure the boiler structure in position. The ferrule is diametrically opposite a threaded opening in the upper wall of the neck in which the spark plug 49 is inserted. The spark plug may be of a special form in which the porcelain extension 50 is sufficiently long to enter the ferrule, and this carries one terminal 51 of the electric circuit and the ferrule may be provided with the opposing terminal 52.

In the construction shown in Fig. 1, the spark plug is above its normal position in respect to the engine cylinder and in some cases this may be undesirable. Therefore by the construction shown in Fig. 4, the spark plug terminals occupy the normal position or practically the normal position of those of the usual plug when inserted in the threaded aperture 45. The ferrule 47 is of tubular form as shown and the gases on the compression stroke of the engine may be forced up into the shell or casing formed by the walls 41 and 42. In this casing is mounted the boiler proper indicated at 53 which may be of comparatively thin metal and provided with a threaded stem 54 at the top of the boiler and a similar stem 55 near the lower end thereof. To these stems are connected respectively the steam and

return lines of the same character as shown in Fig. 1 leading to a radiator. The boiler 53 in the form shown in Fig. 4 is spaced from the wall of the casing as is the relationship of the parts shown in Fig. 1 permitting the gases of combustion to contact the entire exterior surface of the boiler wall 53. This boiler functions in the same manner and is equally as efficient as the form of construction shown in Fig. 1 and is superior in some respects particularly in that the spark plug, although of special form, has the electric terminals in more technically correct position in the cylinder head of the engine. As both devices are equally as efficient and each incorporates the same general features of construction and resultant operation, the invention may be embodied in both these or other forms without departing from the spirit and scope of the invention as set forth in the appended claims.

From the foregoing description it will be evident that the device is simple in form and is readily disassembled by disconnecting the unions 18 with the respective tubes 13 and 19 of the boiler and, by removal of the nut 23 and lock washer 35, the entire structure may be withdrawn through the opening provided in the partition 1 for the sleeve. The boiler element may be removed from the engine head whereupon the spark plug 5 may be re-inserted in the aperture 4 of the engine block. It will also be observed that by use of not more than a half pint of water, a continuous flow of steam will be provided through the line 17 to the radiator and of condensed steam through the return line 20 to the boiler and thus a continuous circulation of the steam in the radiator is maintained. Due to the small quantity of water utilized, the pressures to which the structure is submitted are not sufficiently great to cause disruption of the parts and a quick production of steam results. It has also been found that the engine operates efficiently even through the spark plug 5 be removed a distance from its usual position relative to the combustion chamber of the engine cylinder as the tubular portions 7 and 12 are filled with an explosive gas on the compression stroke. When the fuel charge is fired, there is a considerable flame discharged directly into the combustion chamber and also the burning gases circulate about the walls of the boiler element proper indicated at 11, and thus are in position to be sufficiently heated for the purpose as heretofore stated.

It is to be noted that the boiler structure, which includes the casing 8 as well as the inner boiler shell 11, may be of different form than that shown in the drawings. It is however preferable, whatever the form of the boiler structure may be, that the spark plug 5 should align with the tubular portion 1 supported in the spark plug opening. It is also pointed out that the boiler and radiator element vary in size, firstly for different installations as passenger cars, motor busses, aeroplanes etc., some of which require greater heating capacities than a passenger automobile. Also in the event it is not desired to reduce the water to steam, the boiler element and system may be considerably larger and the boiler element need not have so great a surface exposed to the influence of heat of the combustion gases.

Having thus briefly described my invention, its utility and mode of operation, what I claim and desire to secure by Letters Patent of the United States is—

1. The combination with an internal combustion engine having a cylinder and a spark plug

- opening for the cylinder, of a casing provided with a tubular extension threaded into the spark plug opening, a spark plug mounted in the casing and communicating with the cylinder through the tubular extension of the casing, an annular water tank mounted in the casing about the spark plug and having an opening in the center between the tubular extension and the spark plug, an inlet and an outlet conduit and means associated therewith 5 for supporting the water chamber in spaced relation with the wall of the casing, the inlet and outlet conduits opening into the water chamber.
2. The combination with an internal combustion engine having a cylinder and a spark plug opening for the cylinder, of a casing provided with a tubular extension threaded into the spark plug opening, a spark plug mounted in the casing and communicating with the cylinder through the tubular extension of the casing, a water chamber 10 mounted within the casing, an inlet and an outlet conduit connected to the water chamber and secured to the casing, and means for supporting the water chamber in spaced relation with the wall of the casing.
- 20 3. The combination with an internal combustion engine having a cylinder and a spark plug opening for the cylinder, of a casing provided with a tubular extension threaded into the spark plug opening, a spark plug mounted in the casing and communicating with the cylinder through the tubular extension of the casing, a water chamber 15 mounted within the casing about the spark plug and having an opening in the center between the tubular extension and the spark plug, an inlet and an outlet conduit and means associated therewith for supporting the water chamber in spaced relation with the wall of the casing and spaced from the wall of the casing and an inlet and outlet connection for the water chamber.
4. The combination with an internal combustion engine having a cylinder and a spark plug opening for the cylinder, of a casing threaded into the spark plug opening and open to the interior of the cylinder, an annular water tank mounted in the casing in spaced relation with the wall thereof and a spark plug supported in the casing 20 over the spark plug opening of the cylinder.
5. The combination with an internal combustion engine having a cylinder and a spark plug opening for the cylinder, of a chamber threaded into the spark plug opening and communicating with the interior of the engine cylinder, a water chamber mounted in the casing and spaced from the wall of the casing, an inlet and an outlet conduit for the water chamber, and a spark plug 25 mounted in the casing.

CHARLES E. MORLEY.
